UNITED STATES PATENT OFFICE.

WILLIAM R. FOX, OF GRAND RAPIDS, MICHIGAN.

LINE-LOCK MECHANISM FOR TYPE-WRITERS.

No. 853,965.

Specification of Letters Patent.

Patented May 21, 1907.

Application filed February 1, 1907. Serial No. 355,328.

To all whom it may concern:

Be it known that I, WILLIAM R. FOX, a citizen of the United States, residing at the city of Grand Rapids, county of Kent and State of Michigan, have invented certain new and useful Improvements in Line-Lock Mechanism for Type-Writers, of which the following is a specification.

This invention relates to improvements in typewriters and it relates more particularly to improvements in line lock mechanisms for typewriters whereby the key levers will be effectively locked when the carriage reaches or approaches the end of its predetermined travel.

The objects of this invention are: First: to provide a more direct connection than is usual between the carriage and the key levers; and second: to provide a simple actuating connection between the carriage and the line lock mechanism, whereby the line locking means is easily actuated direct from the connecting lever without a special link to the rocking lock-bar.

Further objects, pertaining to details of construction, will definitely appear from the detailed description to follow.

I accomplish the objects of my invention by the devices and means described in the following specification.

The invention is clearly defined and pointed out in the claims.

A portion of a typewriter necessary to illustrate the structure and nature of my improvements is clearly illustrated in the accompanying drawing forming a part of this specification, in which:

Figure 1 is a longitudinal detail sectional view through the frame of a Fox typewriter, taken on a line corresponding to line 1—1 of Fig. 2, only a portion of the frame being shown and only such portions of the typewriter being shown as are necessary to show clearly my improved line lock mechanism;

Fig. 2 is a rear elevation view of the structure appearing in Fig. 1; Fig. 3 is a detail view of the pivotal connection of the connecting lever 7 of my improved line lock; and Fig. 4 is a detail elevation view of my improved rocking line-locking bar.

In the drawing, the sectional views are taken looking in the direction of the little arrows at the ends of the section lines, and similar numerals of reference refer to similar parts throughout the several views.

Referring to the numbered parts of the drawing, the frame 1 of my improved typewriter is of the usual form of the frame of a Fox typewriter. Transversely through the rear part of the frame is a fulcrum bar 2 to 60 which are fulcrumed by suitable adjustable fulcrums the key levers 3. Beneath these key levers is the rocking locking bar 4, made of sheet metal, the lower edge of which is wrapped around a rod 5, which serves to 65 stiffen the same, the ends of which project and form the pivots thereof, the same entering suitable bearings, preferably in bosses or lugs, or ears, at each side of the frame.

Pivoted on the rear part of the frame on a 70 pivot rod 6 is the actuating lever 7 for the line lock which is bifurcated at its lower end. The under member 7' extends into close proximity to the pivot 5 of the locking bar 4 to actuate the same and throw it upward at a 75 very slight touch or movement, the upper member 7" of the bifurcated part being at some little distance from the center and curved somewhat like a hook, and is so positioned and arranged as to engage over the 80 top of the locking bar 4, when it is thrown into its elevated position to retain it securely in that position, and affords advantage, so that, when the downward pressure at the rear end of the lever 7 is released, the action 85 of the spring 9 will certainly be effective in throwing the upper part of the locking bar 4 forward and downward, so that it will drop readily against the member 7' of the arm 7, well out of reach of the key levers 3. 90

The rear end of the lever 7, which is fulcrumed at 6, projects out to the rear of the machine, and is held normally upward by a comparatively light coiled spring 9, which connects to the rear end thereof and to the 95 upper part of the frame, as is clearly illustrated in Figs. 1 and 2. The stop 16 for the carriage is supported on the locking bar 10, so that it can be rocked out of engagement with the stops 13—13 on the stop bar of the 100 carriage. This stop arm 16 has a bent lever 11 pivoted thereto, which projects somewhat beyond the stop 16 so as to be engaged by the stop 13 toward the right hand side of the machine, so that, when the carriage approaches the end of the line, the stop 13 will engage the lever 11, depressing it toward the stop arm 16. This lever 11 is connected by a link 8 to the line lock lever 7 and, when the 105 lever 11 is actuated, the rear end of the lever 110

7 is depressed, the forward end is thrown upward, and the line locking bar is rocked to the vertical position beneath the key levers 3 and locks them against further movement until the line lock is released.

The line lock is released by actuating the rock shaft 10, by suitable connections to the key board, which throws the stop arm 16 and the lever 11 out of engagement with the stop 10 13, which permits the spring 9 to actuate the line lock lever 7, which throws the rocking line lock bar downward, thereby releasing the keys of the machine.

I desire to remark that my invention pertains to the means here described broadly considered as well as to the specific details.

Having thus described my invention, what I claim as new and desire to secure by Letters Patent is:—

- 20 1. In a line lock for typewriters, the combination of the typewriter frame; the reciprocating carriage thereon; a suitable stop to the rear thereof; a pivoted stop arm 16; an actuating lever pivoted on said stop arm and arranged in the path of the stop, whereby it will be actuated by the stop on the carriage; a line lock lever 7 pivoted in the machine, having a rearwardly extending arm; a spring for holding the rearwardly extending arm 25 normally upward; a connection from the line lock lever to the actuating lever, the line lock lever 7 being provided with a bifurcated lower portion arranged to engage a rocking flat line locking bar, the lower member 7' of said bifurcation extending straight and into close proximity to the axis of the rocking line lock bar, and the upper member 7" being hooked to engage over the top of the bar when in the vertical position, and arranged 30 to depress it when the line lock is released; and a rocking flat line locking bar secured by a suitable pivot at its lower edge within the frame of the typewriter and extending upwardly between the bifurcated members of the line lock member 7 and arranged so that in its vertical position it will prevent the depression of the key levers, all co-acting substantially as described and for the purpose specified.
- 35 2. In a line lock for typewriters, the combination of the typewriter frame; the reciprocating carriage thereon; a suitable stop to the rear thereof; a pivoted stop arm 16; an actuating lever pivoted on said stop arm and arranged in the path of the stop, whereby it will be actuated by the stop on the carriage; a line lock lever 7 pivoted in the machine and having a rearwardly extending arm; means for holding the rearwardly extending arm 40 normally upward; a connection from the line lock lever to the actuating lever, the line lock lever 7 being provided with a bifurcated lower portion arranged to engage a rocking flat line locking bar, the lower member 7' of said bifurcation extending straight and into

close proximity to the axis of the rocking line lock bar, and the upper member 7" being hooked to engage over the top of the bar when in the vertical position and arranged to depress it when the line lock lever is released; and a rocking flat line locking bar 4 secured by a suitable pivot at its lower edge within the frame of the typewriter and extending upwardly between the bifurcated members of the line lock member 7, and arranged so that in its vertical position it will prevent the depression of the key lever, all co-acting substantially as described and for the purpose specified.

3. In the line lock for typewriters, the combination of the typewriter frame; a reciprocating carriage thereon; a suitable stop to the rear thereof; a line lock lever pivoted in the machine and having a rearwardly extending arm; connection from said line lock lever arranged to be actuated by the stop on the reciprocating carriage, the line lock lever 7 being provided with a bifurcated lower portion arranged to engage a rocking, flat, line locking bar, the lower member 7' of said bifurcation extending straight and into close proximity to the axis of the rocking line lock bar, and the upper member 7" being hooked to engage over the top of the bar when in the vertical position and arranged to depress it when the line lock lever is released; and a rocking, flat, line locking bar 4 secured by a suitable pivot at its lower edge within the frame of the typewriter and extending upwardly between the bifurcated members of the line lock member 7 and arranged so that in its vertical position it will prevent the depression of the key lever, all co-acting substantially as described and for the purpose specified.

4. In a line lock for a typewriter, the combination of the typewriter frame; a reciprocating frame thereon; a suitable stop to the rear thereof; a line locking lever fulcrumed in the central portion of said machine, with a rearwardly extending arm with connections arranged to be actuated by the stop of the carriage, and a downwardly extending bifurcated portion for actuating a line lock bar; and a line lock bar arranged beneath the key levers and in position to be engaged by the bifurcated portion, to be actuated by the said lever, co-acting for the purpose specified.

5. In a line lock for typewriters, the combination of the typewriter frame; a reciprocating carriage thereon; a suitable stop thereon; a line locking lever fulcrumed in the central portion of said machine, with connections arranged to be actuated by the stop of the carriage, and a downwardly extending bifurcated portion for actuating a line lock bar; and a line lock bar arranged beneath the key levers and in position to be engaged by the bifurcated portion, to be actuated by

the said lever, co-acting for the purpose specified.

6. In a line lock for typewriters, the combination of the typewriter frame, a reciprocating carriage thereon; a suitable stop thereon; a line locking lever fulcrumed in the central portion of said machine, with connections arranged to be actuated by the stop of the carriage, and a downwardly extending portion bifurcated and arranged to engage a rocking, flat, line locking bar, the lower member 7' of said bifurcation extending straight and into close proximity to the axis of the rocking line lock bar, and the upper member 7" being hooked to engage over the top of the bar when in the vertical position and arranged to depress it when the line lock lever

is released; and a rocking flat line locking bar 4 secured by a suitable pivot at its lower edge within the frame of the typewriter and extending upwardly between the bifurcated members of the line-lock member 7 and arranged so that in its vertical position it will prevent the depression of the key lever, all co-acting substantially as described and for the purpose specified. 20 25

In witness whereof, I have hereunto set my hand and seal in the presence of two witnesses.
